UNITED STATES PATENT OFFICE.

WILLIAM H. H. MUSICK, OF HARTVILLE, MISSOURI.

BRIDGE FOR PRESSES.

No. 841,884.

Specification of Letters Patent.

Patented Jan. 22, 1907.

Application filed June 19, 1906. Serial No. 322,422.

To all whom it may concern:

Be it known that I, WILLIAM H. H. MUSICK, a citizen of the United States, residing at Hartville, in the county of Wright and 5 State of Missouri, have invented a new and useful Bridge for Presses, of which the following is a specification.

This invention relates to a bridge or attachment adapted to be used in connection 10 with an ordinary form of job-printing press, such as is provided with a press-bed, a reciprocating platen, an inking-plate, and inking-rollers adapted to supply ink to the form clamped on the press-bed.

15 In most printing establishments wherein job-presses are employed difficulty is frequently experienced by an old man or a young boy in attempting to fit a heavy chase containing a form of type against the press-bed in the operation of locking it in position, it being understood that in order to fit the form into place it is necessary to hold the same at arm's length and reach over the platen as well as the feed-table.

25 The object of the present invention is to provide a simple, durable, inexpensive, and thoroughly efficient bridge which is adapted to be removably held between the press-bed and the platen, so as to act as a combined 30 support and guide along which the heavy form can be moved in the operation of applying it to the press-bed.

With the foregoing and other objects in view, which will appear as the description 35 proceeds, the invention resides in the combination and arrangement of parts and in the details of construction hereinafter described and claimed, it being understood that changes in the precise embodiment of invention herein disclosed can be made within the 40 scope of the following claims without departing from the spirit of the invention or sacrificing any of its advantages.

In the accompanying drawings, forming 45 part of this specification, Figure 1 is a perspective view of a portion of a job-printing press with the improved attachment of this invention removably fitted between the platen and the press-bed. Fig. 2 is a top 50 plan view of the improved bridge attachment. Fig. 3 is an under plan view thereof. Fig. 4 is a view in elevation looking at the lower edge of the bridge attachment. Fig. 5 is a view similar to Fig. 4, showing a slightly- 55 modified construction. Fig. 6 is a side ele-

vation, partly broken away, of the improved device.

Like reference-numerals indicate corresponding parts in the different figures of the drawings.

It may be premised that the improved press-bridge of this invention can be used in connection with any form of printing-press which is provided with a platen and a press-bed arranged in such manner that difficulty 65 is experienced in applying the form to the press-bed.

For the purpose of conveying a clear understanding of the present invention it has been illustrated in connection with part of an ordinary job-printing press comprising a platen 1, a press-bed 2, an inking-plate 3, and frame 4, which latter forms the sides of the press-bed, as shown.

As is well known, the form of type 5 is suitably locked in the chase 6 of usual form. In applying the form to the press-bed it is necessary to grasp the sides of the chase in the hand, holding the same in a vertical position, with the faces of the type toward the printer 70 and away from the press-bed. The printer then reaches over the platen 1, holding the form at arm's length, and places it against the press-bed 2, where it is locked in position 75 in any suitable manner. As before mentioned, this operation of applying the form is quite difficult when the form is heavy and the printer is not particularly strong.

In order to decrease the difficulty of applying the form to the press-bed, I provide what 90 I term a "bridge" 8, which is supported in any suitable manner between the platen 1 and the press-bed 2, so as to act as a support for the heavy form when it is being applied to the press-bed. The bridge 8 preferably consists of a rectangular plate or board, which may be constructed of any suitable material. On its upper face the bridge 8 is provided with a pair of chase-guides 9 9, which serve to guide the chase and form accurately into position upon the press-bed. The chase-guides 9 9 also act as braces to strengthen the bridge 8, as will be apparent. The chase-guides 9 9 preferably are disposed farthest from each other at their upper ends and converge 95 slightly toward each other from their upper to their lower ends, as shown. The upper ends of the chase-guides 9, preferably are outwardly beveled, as indicated at 10, so as to provide a wide entrance portion for the lower 100 105 110

end of the chase containing the form of type. At their lower ends the chase-guides 9 are provided with beveled projections 11, which fit against the opposite sides 4 of the press-bed 2, so as to prevent the bridge 8 from being laterally misplaced with relation to the press-bed. On its under surface adjacent its upper end the bridge 8 preferably is provided with a pair of bearing-blocks 12, which 10 rest against any suitable portion of the platen 1, so as to support the upper end of the bridge 8. In its lower edge the bridge 8 is formed with a cut-away portion 14, which I shall term a "type-slot," in that its function is to 15 provide a clearance for the projecting faces of the type when they reach the lower edge of the bridge and when the form is tilted upward into vertical position against the press-bed 2. While the upper surface of the bridge 20 8 is usually flat, still in some instances when the faces of the type project a considerable distance beyond the chase it is preferable to form in the upper surface of the bridge a type-channel 15, Fig. 5, which is deep enough to 25 receive the faces of the type without permitting them to scratch against the upper surface of the bridge, it being understood that the sides of the chase 6 when the channel 15 is employed will rest upon the ledges 16 at 30 the sides of the type-channel 15. When the type-channel 15 is used, the chase containing the form of type can be placed face downward upon the bridge 8, with the type projecting into the channel 15. The chase is then 35 slid downward upon the upper surface of the bridge 8 until its lower edge engages the press-bed 2. The rear upper edge of the chase is then swung upward, so that the form of type is disposed flat against the press-bed 2, as 40 will be understood. The bridge 8 of course is then removed and the ink-rollers, which it is usually necessary to move out of the way when it is desired to change the form of type, are replaced in position to supply ink to the 45 form. The press is then in condition for use. When it is desired to remove the form, the bridge 8 is again placed in position and utilized as a support up which the form is drawn after it has been disengaged from the press-bed.

As before explained, the bridge 8 can be supported between the press-bed 2 and the platen 1 in any suitable manner. In some forms of printing presses the lower end of the bridge 8 can rest upon and be supported by the saddle-pieces which carry the ink-rollers. The preferred means, however, which I use for supporting the bridge 8 consists of a pair of supporting devices 20, which are in the 55 form of rods having threaded lower ends extending through the chase-guides 9 and bridge 8 and being provided above and below the bridge with retaining-nuts 21. At their upper ends the rods 20 are bent, as indicated at 60 22, to form hooks which are adapted to en-

gage the recessed portion 23 in the rear edges of the frame 4, which forms the sides of the press-bed. It will be understood that the supporting devices or rods 20 can be readily engaged with or disengaged from the printing-press by loosening their nuts and rotating them slightly, so that their hooks 20 will become engaged with or disengaged from the press. 70

The bridge attachment of this invention is 75 strong, simple, durable, and inexpensive in construction, as well as thoroughly efficient in operation.

As shown in Fig. 6, the rear end of the bridge 8 adjacent the bearing-blocks 12 may 80 be recessed slightly, as indicated at 12', to receive the forward edge of the platen 1, in which case the bearing-blocks 12 will engage the forward vertical edge of said platen, so as to prevent any rearward slipping of the bridge 85 upon the platen.

In most forms of presses it will be desirable to incline the supporting devices 20 slightly rearward, as shown in Fig. 6.

What is claimed is—

1. The combination with a printing-press having a press-bed and a platen, of a removable bridge arranged and adapted to form a temporary support for receiving a chase during the placing and removal thereof. 90

2. The combination with a printing-press having a press-bed and platen, of a removable bridge having one end located adjacent the press-bed and the other end located adjacent the platen. 100

3. The combination with a printing-press having a press-bed and a platen, of a removable bridge arranged and adapted to form a temporary support for a chase to rest on during the placing or removal thereof, and guides 105 on the bridge for the chase.

4. The combination with a printing-press having a press-bed and platen, of a removable bridge having converging form or chase guides. 110

5. The combination with a printing-press having a press-bed and platen, of a removable bridge having converging form or chase guides provided with beveled upper ends. 115

6. The combination with a printing-press having a platen and a press-bed, of a bridge adapted to be placed over the platen only during the positioning or removal of the chase and having chase-guides provided with projections adapted to engage the sides of the 120 press-bed.

7. The combination with a printing-press having a platen and a press-bed, of a removable bridge forming a temporary support for a chase and mounted between the platen and the press-bed and having a type-slot in its lower end. 125

8. The combination with a printing-press having a platen and a press-bed, of a removable bridge forming a temporary support for 130

a chase and mounted between the platen and the press-bed and having a type-slot in its lower end and a type-channel in its upper surface.

5 9. The combination with a printing-press having a platen and a press-bed, of a bridge forming a temporary support for a chase and located between the platen and the press-bed, and means for holding the bridge in proper

10 position.

10. The combination with a printing-press having a platen and a press-bed, of a bridge forming a temporary support for a chase and located between the platen and the press-bed, and supporting devices connected with the bridge and engaging the sides of the press-bed.

15 11. The combination with a printing-press having a platen and a press-bed, of a bridge located between the platen and the press-

bed, said bridge having combined guides and braces on its upper surface, bearing-blocks on its under surface, a type-slot in its lower edge, a type-channel in its upper surface, and hook-rods extending through the combined braces 25 and guides and through the bridge.

12. As an article of manufacture, a press-bridge forming a temporary support for a chase during the positioning thereof in a press or removal of the chase therefrom, 30 chase-guides on the upper surface of the bridge, and a type-slot at the lower edge of the latter.

In testimony that I claim the foregoing as my own I have hereto affixed my signature in 35 the presence of two witnesses.

WILLIAM H. H. MUSICK.
